UNITED STATES PATENT OFFICE.

ARTHUR SNOWDEN, OF VANCOUVER, BRITISH COLUMBIA, CANADA.

MEASURING PUMP FOR SERVICE STATIONS.

Application filed November 6, 1924. Serial No. 748,193.

To all whom it may concern:

Be it known that I, ARTHUR SNOWDEN, a subject of the King of Great Britain, and a resident of the city of Vancouver, in the 5 Province of British Columbia, Canada, have invented certain new and useful Improvements in Measuring Pumps for Service Stations, of which the following is a specification.

10 My invention relates to improvements in measuring pumps for service stations, the objects of which are to provide means whereby the necessity of reversing the action of the pump by releasing the operating gear 15 from the pump cylinder is avoided, and also to provide means whereby the pump action is arrested when the desired quantity of liquid is delivered.

The invention consists essentially of a 20 multiple cylinder pump having a driven screw connected to its operating mechanism upon which a traveller is adapted to travel longitudinally until it reaches an adjustable stop, which is set to any desired gallonage, 25 as will be more fully described in the following specification, in which:—

Fig. 1 is a general view of the operating mechanism of the pump, showing a part of the pump barrels.

30 Fig. 2 is a sectional view taken on the line 2—2 of Figure 1.

In the drawings like characters of reference indicate corresponding parts in each figure.

35 The numeral 1 indicates a pair of pump cylinders capable of delivering a given delivery of liquid per stroke. 2 are the piston rods and 3 the connecting rods therefor.

The numeral 4 indicates a pair of standards upon which the operating and measuring mechanism is carried. The numeral 5 indicates a main shaft having a pair of crank discs 6 and 6^A to each of which a connecting rod 3 is operably mounted. The 45 shaft 5 is provided with a gear 7 which is

driven through an intermediate gear 8 by a pinion 9 upon a shaft 10, which shaft is rotated by a hand crank 11. The intermediate gear 8 is mounted upon a shaft 12 which is 50 provided with a worm 13 having a definite number of turns to each unit of measurement, the purpose of which will hereinafter appear.

The numeral 14 indicates a circular bar 55 having a square shank 15 which is slidably carried by the standards 4. The shank is

fitted to a square aperture 16 to prevent rotation, and is adapted for endwise movement, the end of the shank being normally held by a compression spring 17 away from 60 the adjacent disc 6^A.

A plurality of keys 18 are set longitudinally of the bar 14 and are spaced apart to distances equivalent to the lead of the worm required to represent units of measurement 65 of the pump delivery, and a collar 19 is slidably mounted upon the bar which is provided with a key way 20 somewhat larger than the keys 18, so that it may be moved along the bar and brought to rest against 70 any one of the keys by rotating it until the keys and keyway are out of register with each other. A boss 21 is formed on the face of the collar to engage any one of the keys 18 to prevent the projecting stop 22 from 75 falling beyond a horizontal position as shown in Figure 2.

The numeral 23 indicates a radial slot formed in the inner face of the disc 6^A, the bottom of which is inclined to correspond 80 with the pitch of the worm 13.

Parallel to the shaft 8 a guide bar 24 is fitted, upon which a traveller 25 is endwise movable. The traveller is provided with a threaded half sleeve 26 which is 85 adapted to engage the worm 13, and 27 is a stop which is adapted to engage the projection 22 of the collar 21 when the traveller is nearing its predetermined endwise movement upon the worm 13. Following the contact being made between the traveller and the collar 21, endwise movement is imparted to the bar 14 against the spring 17, causing the square shank 15 to enter the radial slot 90 23 in the disc 6^A, and to continue to project thereinto until the rotation of the disc is arrested by the end 28 of the slot 23 coming into engagement with the side of the shank 15, thus bringing the pump mechanism to 95 rest and stopping the flow of liquid therefrom.

When it is desired to deliver a given quantity equal to, or less than the total graduations (represented by the keys 18) provided, the collar is rotated and set adjacent the desired key and the traveller raised and set back at the starting end of the worm 14 and the hand crank 11 is rotated in a forward direction until the disc 6^A is again stopped as above described.

Should it be desired to discharge a quantity of liquid greater than the quantity

prescribed by the unit measurement, the traveller 25 may be raised and the pump operated continuously, one cylinder delivering while the piston is being returned in the other one.

It will thus be seen that I have invented a measuring pump which can be set to discharge a given gallonage or to discharge a continuous stream as desired, and one in 10 which the releasing of the pump piston from the operating mechanism is dispensed with.

What I claim as my invention is:

1. In a measuring pump capable of continuous delivery and having cylinders operated through one or more crank discs upon a driven shaft, a rod divided into units of measurement fitted adjacent a disc and having endwise movement, a collar carried by 20 said rod adjustable to any of said units, means actuated by the pump mechanism adapted to engage the collar and to move the rod into engagement with a crank disc to prevent its rotation when the indicated 25 delivery is attained.

2. In a measuring pump capable of continuous delivery, a rod divided into units of

measurement of the pump delivery and capable of endwise movement, a collar adjustable to any of said units, a worm actuated 30 by the pump operating mechanism and having a traveller movable therealong to engage the collar and move the rod in order to stop the operation of the pump when the desired delivery is attained.

3. In a measuring pump capable of continuous delivery, a rod divided into units of measurement of the pump delivery and capable of endwise movement, a collar adjustable to any of said units, a worm actuated 40 by the pump operating mechanism and having a traveller movable therealong in one direction to engage the collar and move the rod in order to stop the operation of the pump when the desired delivery is attained, and means for return the traveller to its starting point upon the worm.

Dated at Vancouver, B. C., this 24 day of October, 1924.

ARTHUR SNOWDEN.
